UNITED STATES PATENT OFFICE.

THOMAS McDOWELL AND JAMES BENGOUGH, OF NIAGARA FALLS, NEW YORK, ASSIGNORS TO THE CARTER-CRUME COMPANY, OF SAME PLACE.

PAPER-FOLDING APPARATUS.

SPECIFICATION forming part of Letters Patent No. 630,626, dated August 8, 1899.

Application filed September 23, 1896. Serial No. 606,720. (No model.)

To all whom it may concern:

Be it known that we, THOMAS McDOWELL and JAMES BENGOUGH, of Niagara Falls, in the county of Niagara, in the State of New York, have invented new and useful Improvements in Paper-Folding Apparatus, of which the following, taken in connection with the accompanying drawings, is a full, clear, and exact description.

10 Our invention relates to paper-folding apparatus particularly for use in connection with printing-machines; and the object is to provide a paper-folding device suitable for folding the triplicate leaves of what are known 15 as "triplicate" copying or blank books.

To this end our invention consists in the combination, with the frame, of a head carrying feed-rolls for the paper, a bed for the paper in the frame, a spring-clamp having

20 guide-rods extending through the frame, springs on the rods to hold the clamp in its raised position, a knife to cut the paper, links to support the knife upon the frame, a spring to raise the knife, suitable means to depress 25 the knife, and a projection on the knife to depress the clamp when the knife is depressed; and our invention consists in certain other combinations of parts hereinafter described, and specifically set forth in the claims.

30 In the drawings hereto annexed and forming a part of this specification, Figure 1 is a side elevation of our folding apparatus, which is shown connected to one end of an ordinary printing-press employed for printing memorandum-slips for copying-books. Fig. 2 is a top plan view of the rear angular frame and the back head containing paper-feed rolls. Fig. 3 is a top plan view of the apparatus with a portion of the frame broken away. Fig. 4 40 is an enlarged front-side view of the front head, showing the cutting devices. Fig. 5 shows the clamping device which operates in conjunction with the cutting device. Fig. 6 is a sectional view of the front head containing feed-rolls, taken on line $x-x$ of Fig. 4. Fig. 7 is a front-side elevation of the back head, the central part thereof being broken away. Fig. 8 shows a triplicate leaf entirely unfolded. Fig. 9 shows the edge of the leaf 45 or web of paper as it appears after it has

passed over the first angular frame and is lying between the feed-rolls of the back head; and Fig. 10 shows the same after it has passed over the second angular frame and is lying between the rolls of the front head of the apparatus, and, in fact, shows precisely an edge view of the triplicate or double-folded leaf as it appears after it is cut off or separated from the web.

55 Referring specifically to the drawings, W is the web of paper, passing to the left or in the direction of the arrows from between a pair of feed or delivering rolls s and s' , extending horizontally across the end of a printing-press S .

60 A and A' are the angular frames, arranged one in advance of the other, and over and around which the paper passes to fold the same.

65 B is the back head, or the head located between the pair of angular frames, and B' is the front head, or the head through which the paper passes after it has been folded twice. The said angular frames each comprise a pair of bars joined together at one end and forming 70 an acute angle at the junction, with cross-bars between them, to which the supporting post or standard a or a' is secured, which post or standard is mounted on its respective head, or the head located in close proximity to the 75 point of the angular frame.

70 The faces of the frames A and A' are arranged at right angles to each other, A being in an inclined horizontal plane and A' in an inclined vertical plane, as clearly shown in 80 the drawings. The points of the frames extend to one end of their respective heads and are out of line, so that the paper W will be folded on the broken lines $y y'$, running lengthwise of the web between and parallel 85 with its side edges. The web is folded in substantially a Z shape or zigzag form, as illustrated in Figs. 4 and 10 of the drawings. Usually the web is perforated or indented on these lines $y y'$ before it leaves the printing- 90 press S . It will be noticed that one of the end sections of the leaf is longer than the other sections for the purpose of binding a series of leaves together to form the book.

95 The heads containing the feed-rolls and 100

- compressing-rolls are substantially the same in construction, except that the back head is longer than the other and is not provided with the cutting devices, clamping devices, and 5 gripping-fingers, to be hereinafter described. The back head B stands in a vertical position and is adjustably supported at its lower end upon a grooved horizontal cross-bar X' of the frame X. Journaled at its ends and extending vertically are a pair of compressing-rolls c c' or simple rods to bear on opposite sides of the web and also a pair of shafts d d' in advance of the rods or compressing-rolls, each containing a pair of rolls b b' or circumferentially-enlarged portions on the shafts and which constitute the feed-rolls. These paper-feed rolls are on opposite sides of the paper, which when passing between them is folded on the line y.
- 20 The heads B and B' are adjusted or moved laterally on the grooved cross-bars X' X' by simply loosening the bolts t t and shifting the heads to one side or the other and then tightening the said bolts. The beveled gears upon 25 the shafts Y' and w', which drive the feed-rolls of the heads B and B', are shifted correspondingly by any suitable and well-known means not necessary to be described.
- 20 The rotatable shaft d' is stationary in the head and receives motion by means of beveled gears d'' at its lower end, an inclined shaft Y, extending from the paper-feed roll s of the printing-machine, and a horizontal shaft Y', extending below and parallel with the 30 grooved bar X'. The upper ends of the feed-roll shafts are provided with gear-wheels c'', in mesh with each other, so that the shafts are driven in opposite directions to carry the paper between them. The shaft d is journaled in short arms d''', pivoted to the frame of the head, the free ends of the arms being connected to coiled springs c''', (shown in Fig. 2,) which allows the shaft d, with its rolls, and also the compressing-rolls c', to bear yieldingly against the stationary rolls on the opposite side of the paper. This operation is due to the fact that the roll referred to is mounted in the pivoted frame which carries one of the feed-rolls. At the diverging ends of the angular frames A and A' are small rollers e and e' to hold the paper flat against the faces of the frames. The latter roll e' is journaled to the front side of the back head. The front head being substantially the same in construction as the back head, except that the former lies in a horizontal position and is shorter, as when the paper passes through it the paper has been folded twice, it will be unnecessary to describe it at length, except in 55 connection with the devices attached thereto for clamping and cutting the paper as it emerges from the head. We will say, first, however, that the feed-rolls of the front head receive motion through beveled gears b', a vertical shaft w, carried by the frame of the head, a horizontal cross-shaft w' below, and an in-
- clined shaft w'', extending between the said cross-shaft and the shaft Y', before referred to, all of said shafts being suitably supported to turn in brackets secured to the frame X, 70 as shown.
- In the front head B', below where the paper emerges, is a bed C, and above this bed is a horizontal plate D, secured to the lower ends of a pair of vertical rods E E, extending upward through a horizontal bar E', fixed upon the upper part of the frame of the head. The plate D is the clamping-plate which forces the paper down upon the bed C and holds it there while the knife operates to sever the 80 folded leaf from the web. The clamping-plate D is raised from the paper to allow it to be moved along the width of another leaf by means of coiled springs f f' on the rods E between the bar E' and pins f' f'', extending 85 through the upper ends of the rods. Between the rods E E are a pair of blocks g g, secured to the plate D, and extending between the blocks is a horizontal spring-bar g', having a curved spring g'', secured centrally to its 90 lower side, the ends of the curved spring bearing upon the plate D. The clamping-plate D is forced downward by means of a small roller q on the inside of the knife and bearing upon the horizontal spring of the 95 clamp. The clamp presses the paper upon the bed C just before the knife F begins to cut, and its pressure is increased slightly during the cutting operation.
- The knife F is secured to the rear side of 100 the slightly-inclined cutting-bar F' and engages a plate F'', secured to the front side of the bed C. The knife-bar F' is connected by links h h with the frame of the head, one of said links being fulcrumed slightly higher 105 than the other to incline the cutting-bar and its knife. A coiled spring h' connects one of the links with the frame and serves to raise the knife after it has been depressed. The knife-bar F' is depressed by means of a rod 110 G, secured to one end of the bar and extending downward to an arm G' on a shaft H. The shaft H is provided with an arm H', which is connected by a rod I (shown partly by broken lines in Fig. 1) with a bell-crank 115 lever I' on one side of the printing-machine S. One arm of the bell-crank lever is slotted to allow the rod I to be adjusted thereon to vary the depression of the knife. The other arm of the lever I' is connected to a vertical 120 rod J and a slotted plate J', through which slot a horizontal shaft V of the printing-machine extends. A pair of cams i i on this shaft and on opposite sides of the plate J' engage small rollers i' i' on opposite sides of the 125 plate and serve to reciprocate the plate and operate the bell-crank lever I'. Although the shaft V rotates continuously, these cams cause the knife F to operate intermittently and when the paper is not in motion.
- K is a pocket secured to the front head to 130 hold the folded leaves when they are cut off.

One of said leaves is shown lying on the bottom of the pocket, while another leaf is shown ready to be cut off.

A pair of wire fingers *j j*, having coiled springs formed on their ends, are mounted on a shaft *k*, supported in the ends of extensions *l l* of the pocket *K*. The fingers serve to carry the folded leaf downward to the pile after it is cut off. The fingers are operated by means of a connecting-rod *m*, extending downward from an arm *n* on the shaft *k* to an arm *p*, mounted on the shaft *H*, before referred to, the shaft *H* being the shaft that operates the cutting-bar *F*.

5 Instead of connecting the rod *I* and shaft *Y* with the parts of the printing-machine, as shown, they may be connected with other suitable movable parts thereof which will transmit the required intermittent motion to the feeding and cutting devices of the folding apparatus.

We do not desire to be limited to the precise form of construction herein shown and described, as it will be obvious that the same 25 may be changed without departing from our invention.

Having described our invention, what we claim as new, and desire to secure by Letters Patent, is—

30 1. In a paper-folding apparatus, the combination with the frame having a grooved cross-bar, a head movable and adjustable upon said cross-bar, a pair of parallel shafts provided with circumferentially-enlarged portions constituting the feed-rolls carried by said head, one of said rolls being supported yieldingly, a spring to force the rolls together, gear-wheels connecting the feed-rolls together, a driving-shaft connected to one of the feed-40 rolls, a pair of rods parallel with the feed-

rolls also yielding relatively to each other, an angular frame having an acute angle supported on said head with the said angle extending toward one end of the feed-rolls, and a roller journaled on the opposite side of the 45 head parallel with the feed-rolls, as set forth.

2. The combination with the frame, of a head carrying feed-rolls for the paper, a bed for the paper in the frame, a spring-clamp having guide-rods extending through the 50 frame, springs on the rods to hold the clamp in its raised position, a knife to cut the paper, links to support the knife upon the frame, a spring to raise the knife, suitable means to depress the knife, and a projection on the 55 knife to depress the clamp when the knife is depressed, as set forth.

3. The combination with the frame, of a head carrying feed-rolls for the paper, a bed for the paper in the frame, a spring-clamp 60 having guide-rods extending through the frame, springs on the rods to hold the clamp in its raised position, a knife to cut the paper, links to support the knife upon the frame, a spring to raise the knife, suitable means to 65 depress the knife, a projection on the inner side of the knife to engage the clamp, a pocket to receive the portions of paper cut off, fingers mounted on a shaft to carry the portions of paper from the knife to the pocket, and 70 means to operate the said shaft connected to one of the shafts for operating the knife, as set forth.

In testimony whereof we have hereunto signed our names.

THOMAS McDOWELL. [L. S.]
JAMES BENGOUGH. [L. S.]
